UNITED STATES PATENT OFFICE

172,168

SURFACE CLEANING MACHINE

William G. Meagher, Oakland, Calif.

Application September 14, 1953, Serial No. 26,790

Term of patent 14 years

(Cl. D9—2)

To all whom it may concern:

Be it known that I, William G. Meagher, a citizen of the United States, residing at Oakland, Alameda County, State of California, have invented a new, original, and ornamental Design for a Surface Cleaning Machine, of which the following is a specification, reference being had to the accompanying drawing, forming a part hereof, wherein,

Figure 1 is a perspective view of a surface cleaning machine, embodying my new design.

Figure 2 is a perspective view of the machine in inverted position with respect to its position of Figure 1.

I claim:

The ornamental design for a surface cleaning machine, substantially as shown.
